UNITED STATES PATENT OFFICE.

KARL G. WALKER, OF SEWICKLEY, PENNSYLVANIA, ASSIGNOR, BY MESNE ASSIGNMENTS, TO WILLIAM S. LAWSON, JR., OF NEW YORK, N. Y.

APPARATUS FOR DRILLING NON-CIRCULAR HOLES.

1,359,129.

Specification of Letters Patent. Patented Nov. 16, 1920.

Application filed September 10, 1918. Serial No. 253,434.

To all whom it may concern:

Be it known that I, KARL G. WALKER, a citizen of the United States, residing at Sewickley, in the county of Allegheny and 5 State of Pennsylvania, have invented certain new and useful Improvements in Apparatus for Drilling Non-Circular Holes, of which the following is a specification.

My invention relates to apparatus used 10 in drilling or boring non-circular holes. In tools of this character the drill, which is rotated from the driving spindle is given lateral movements to properly shape the particular hole the apparatus is intended 15 to produce, the lateral movements being given to the drill or boring tool by a guide. As apparatus and machines of this general character are now well known in the art I shall not describe the principle on which 20 they operate, nor have I illustrated many of the features which are common and constitute no part of my invention.

The invention has for its object to produce a self-contained apparatus for the 25 purpose above referred to.

To secure the objects of the invention the parts of the apparatus in which it is embodied are arranged and combined in a manner that will be described, in order to secure 30 accuracy, stability and efficiency in operation, and to reduce to a minimum wear upon parts, while arranging such parts as are particularly subject to wear so they may be conveniently taken out and replaced 35 when they become defective through breakage or wear. The pattern or guide that controls the lateral movement of the drilling tool and thus determines the shape of the hole produced is adjustably mounted in 40 a support adapted to be rigidly, though adjustably, secured to a part of the machine that carries it, this support being especially constructed to support the pattern or tool guide and also to constitute a closed housing 45 for the driving head through which the tool is rotated.

I have illustrated my invention as applied to a machine or apparatus in which there is no relative axial movement between 50 the pattern and the driven spindle or drilling tool, it being contemplated, in such a machine, that the work shall move toward the tool, rather than the latter toward the work. It should, however, be understood 55 that the invention is equally applicable to

machines in which the work is held on a stationary support and the drill is moved axially relative thereto.

In the accompanying drawings Figure 1 is a vertical sectional view of apparatus 60 embodying my invention.

Fig. 2 is an end view.

Fig. 3 is an elevation, and

Fig. 4 is an end view of the driving head for the drill.

Figs. 5 to 11 are detail views of parts detached.

In the drawings, 2 indicates the driving head for the drill or boring tool, it being provided with a shank 3, preferably tapering, and adapted to fit the rotating spindle of the drill or other machine to which the apparatus is applied. The head is recessed as indicated at 4, its open end being covered by a retaining plate 5 suitably secured to 70 the head so as to be removable at will. The plate 5 has a hole 6 through it for the passage of the drill, the hole being of a size to permit the drill to have the necessary free lateral movements. The inner 80 end of the drill 7 has secured to it a driving piece 8, Figs. 9 and 10, formed with a tongue 9 that is adapted to lie inside the inturned shoulder or flange 10 of the driving head 2. This driving piece is formed 85 with a lug 12 adapted to lie in a recess 28, Fig. 11, formed in the shoulder 10 of the driving head. 17, Figs. 7 and 8, indicates a replaceable driving block seated in the recess 18 where it is secured by screw 90 19 or other suitable means, permitting it to be easily removed and replaced and yet securely held when in working position.

The driving block 17 should be formed of extremely hard metal to resist wear, and is 95 arranged to act directly against the flat face of the lug 12 of the driving piece that is secured to the end of the drill, and these constitute the driving members between the rotating head 2 and the tool 7. The end 100 of the drill bears against a wear plate 13 located between the driving piece 8 and the inner face of the driving head, and free to move with the drill as it is moved laterally under the action of the pattern guide 105 that determines the shape and size of the aperture being formed. This wear plate is preferably formed with a central stud-like part 14 that lies within the central reduced portion 15 of the main recess 4 in the driv- 110

ing head. It is also formed with an annular ridge 29 that bears against the face of a plate 16 formed of hard wear-resisting metal seated in the head 2 concentric with the axis thereof. In the face of the wear plate 13 toward the end of the drill, is preferably formed a shallow curved recess with which the end of the drill engages, permitting a slight rolling motion between the drill and this plate without tipping the latter should there be any misalignment of the parts when in use.

20 designates a support for carrying the adjustable pattern pieces 21 that constitute 15 the guide which gives to the drill its lateral movements relative to the axis of rotation of the head and which determines the size and shape of the aperture the drill forms. It is provided with an outwardly 20 extending flange 22, slotted at 23 for the passage of bolts or other attaching means by which it may be secured to a suitable support, such as the framework of the machine, and to allow for angular adjustment. 25 The support is centrally recessed, in line with the opening through the drill guide, as at 23, to receive the driving head 2 and the end of the driving spindle, it thus constituting a protecting housing for these 30 driving parts. The end of the support 20 is slotted to form parallel walls 30 between which lie the two pattern members 21 forming the drill guide, and by which these members are properly directed in their 35 adjustments toward and from each other. Each drill guide member is formed with a screw-threaded recess 31, the threads of the recesses in the two guides inclining in opposite directions when the guides are located 40 in working position within the slotted portion of the support 20. These screw-threaded parts of the guide members engage oppositely inclined screw-threaded parts 32 of a guide-adjusting stem 24 45 mounted in the support 20 so that it is free to be rotated, without, however, moving longitudinally. The stem is provided with an operating handle 33. A clamp 35 engages with a circumferentially recessed part 50 of the stem 24, between the screws 32 thereof, and operates to hold the stem in place after it has been adjusted to properly set the guide pieces 21. A screw 25 seated in a collar 26, operates the clamp. The 55 form of guide for the drill tool shown in the drawings and the means for adjusting it are typical, and my invention is not limited to these features.

60 A split collar 26 is applied to the outside of the support 20, which is preferably reduced to receive the collar, as represented in Fig. 1. The collar is clamped in place upon the support by the screws 27 and serves to strengthen the support and at the same time 65 to close the open ends of the slot in which

lie the members 21 constituting the drill guide, as clearly shown in Fig. 2. The collar thus limits the radial movements, in outward directions, of the pattern guide pieces, which are shown in engagement with the collar, in Fig. 2, the pattern guide thus being represented as adjusted to form the largest opening possible with the guide shown in the drawings. By operating the adjusting screw stem 24 the guides may be 75 caused to approach each other, reducing the open space between them and hence making the pattern smaller so that the drill will form a smaller hole. Adjusting screws 80 seated in the collar 26, bear respectively against the guide members 21 and prevent them from moving outwardly during use. The screws 40 are locked in position after they have been adjusted to engage with the guide members 21 by wing nuts 36. A gib 85 37 may be employed between the guide-forming members 21 and the support 20 to take up wear. Screws 38 act upon this gib. The outer ends of the guide members 21 are preferably reduced as indicated at 39, 90 and with these parts there engages a ring 41 secured to the support 20, as represented in Figs. 1 and 2, and located partly in a recess formed therefor in the outer end of the support and partly between the collar 95 26 and the said reduced portions of the guide members 21.

In assembling the parts of the apparatus the pattern or guide members 21 are inserted in the slotted portion of the support 20 100 and are drawn into place by means of the right and left hand screw-threaded stem 24. The collar 26 and the ring 41 are then applied and secured.

What I claim is:

1. In apparatus for drilling non-circular holes, a driving piece secured to the end of the drilling tool, a driving head adapted to be rotated and arranged to engage with the said driving piece to rotate the drill, a removable wearing plate seated in the driving head, and a wearing piece to take the thrust of the drilling tool interposed between the latter and the wearing plate and having a concentric ridge adapted to bear upon such plate and slide laterally over the face thereof.

2. In apparatus for drilling non-circular holes, a driving piece secured to the end of the drilling tool, a rotating driving head arranged to engage with the driving piece to rotate the tool, a removable wear plate secured in the driving head, and a wear piece to take the thrust of the driving tool, interposed between the latter and the wear plate and having a concentric ridge adapted to bear upon such plate, the engagement between the drilling tool and the wear plate permitting a slight rolling motion between them so that slight misalignment between the 130

tool and the driving head will not affect the operation of the tool.

3. In apparatus for drilling non-circular holes, a recessed driving head, the opening 5 of the recess being surrounded by an in-turned shoulder in which is formed a recess, a driving piece secured to the drilling tool adapted to lie within the recess of the driving head and formed with a laterally extending lug that is to lie within the recess in 10 the inturned portion of the driving head, and a removable wear-resisting driving block secured to the driving head and adapted to engage with the lug of the driving piece.

4. In apparatus for drilling non-circular holes the combination with the drilling tool, means for rotating it and a guide for giving to the tool its lateral movements, of a 20 slotted support for the guide and a strengthening collar surrounding the slotted portion of the support carrying the guide and secured thereto.

5. In apparatus for drilling non-circular 25 holes, the combination with the drilling tool, means for rotating it, and an adjust-

able guide for giving to the tool its lateral movements, of a support for the guide having a slotted portion in which the parts of the guide are supported, means for adjusting these parts to change the form of the 30 guide, and a collar surrounding the slotted portion of the support, in which the tool guide is mounted, arranged to close the ends of the slot in which the guide lies, and also 35 serving to strengthen the slotted part of the support.

6. In apparatus for drilling non-circular holes, the combination with a drilling tool, means for rotating it and an adjustable 40 guide for giving to the tool lateral movements, of a slotted support to receive the adjustable guide, means for adjusting the parts of the guide, a strengthening collar surrounding the slotted portion of the 45 guide, strengthening the support and closing the ends of the slot in which the guide lies, and adjustable means for holding the parts of the guide in place and against outward movement by the tool while it is being 50 rotated.

KARL G. WALKER.
